ATTORNEY

UNITED STATES PATENT OFFICE.

RICHARD B. CHAMBERS, OF CHESTER, PENNSYLVANIA, ASSIGNOR TO
CROSBY M. BLACK, OF SAME PLACE.

COMBINATION PENCIL SHARPENER, GRINDER, PROTECTOR, AND ERASER.

SPECIFICATION forming part of Letters Patent No. 521,016, dated June 5, 1894.

Application filed March 6, 1894. Serial No. 502,545. (No model.)

To all whom it may concern:

Be it known that I, RICHARD B. CHAMBERS, a citizen of the United States, residing at Chester, in the county of Delaware and State of Pennsylvania, have invented a new Improvement 5 in a Combination Pencil Sharpener, Grinder, Protector, and Eraser, of which the following is a specification.

My invention relates to a pencil sharpener, 10 in which is arranged a longitudinal cutting knife, placed at a suitable angle within a tube, slightly above its base, and having a beveled opening or slot for the escape of the shavings, and having its opening above the cutting 15 knife, not confined, but left the full size of the tube, the sides of the tube having an oval or other suitably shaped opening on each side, around which is arranged a flexible or other belt of suitable material, having its inner side 20 coated with emery, or its equivalent above which at the end of the tube, a pencil eraser is secured.

My invention has for its object, to provide 25 an efficient device for sharpening pencils, that will be adapted for use with lead pencils and slate pencils, or their equivalent, mounted in wood, or any other material, and by the peculiar construction, to remove the liability of breaking the lead, or other material composing 30 the pencil.

I attain the objects of my invention by the mechanism and peculiar construction, illustrated in the accompanying drawings.

Figure 1 is a front side elevation, taken 35 from the knife side. Fig. 2 is a side elevation showing reverse side. Fig. 3 is an open elevation or side view. Fig. 3^a is a detail sectional view of the cutting knife tube and the cutting knife.

In Fig. 1, A A represent two guiding spring 40 clips attached to the cutting knife tube B, and forming a flange or base C for the knife tube or chamber B.

D is the longitudinal knife blade, securely 45 fastened at a slightly angular position toward the center of the chamber B. This arrangement of the cutting knife blade D removes the danger of cutting off or breaking the point of the pencil, and the shaving is planed 50 off straight, and passed out by the beveled

slot E. The pencil point, after passing the knife D has a free space above in the upper part of the chamber B, above the knife, and is maintained in a true and parallel position by the guides A A. The upper part of the 55 chamber or tube B, above the knife, is cut out on each side as shown by the dotted openings at F. See Figs. 2 and 3. In Fig. 1 these openings are concealed by the tube being entirely encircled by the flexible belt or sleeve 60 G, having its inner side lined or coated with emery, or its equivalent. On the pencil H being inserted between and encircled by the guides A A and passed upward to the chamber or tube B, and rotated toward the cutting 65 knife D, the wood, or its equivalent, forming the jacket of the pencil, will be planed off, and if too much pressure is brought to bear on the pencil, it will force itself away from the knife and thereby remove the risk of 70 breaking off the point. When the end of the pencil H has been sufficiently planed or reduced to the desired degree, the construction of the tube or chamber B, permits of the point being pushed upward to a point at 75 J, Fig. 2, opposite the openings F F, and the flexible belt or sleeve G being compressed and forced in or through the openings F F by the pressure of the operator's thumb and finger. The inner side of the flexible belt or 80 grinding sleeve G with its emery coating, comes in contact with the point of the pencil, and by the application of the equal pressure brought to bear on the belt by the grip of the thumb and finger, the pencil on being 85 revolved, is given a smooth and finely finished point. K K in Fig. 1 are two spring guards, secured at their base, to guard against liability of losing off the grinding sleeve G, and are left detached at one end to facilitate 90 removal, or for replacing with new ones when required.

Having described my invention, what I desire to secure by Letters Patent is—

1. The tube B, having the clamping guides 95 A A, and a cutting knife D, inclined angularly toward the center of tube B, said tube having the openings F F on opposite sides and provided with the spring guards K K, the abrading sleeve G, and the beveled slot 100

E, substantially as shown and for the purpose specified.

2. In combination with the tube B, having guides A A and the openings F F, the flexible belt or sleeve G, having its inner side lined or coated with emery or its equivalent, and the eraser g, held in said sleeve all substantially as shown and described.

In testimony whereof I have affixed my signature in the presence of two subscribing witnesses.

RICHARD B. CHAMBERS.
